DESIGN FOR A HAT

Andrew A. Syzdek, Amsterdam, N. Y.

Application December 21, 1943, Serial No. 112,067

Term of patent 3½ years

(Cl. D3—13)

To all whom it may concern:

Be it known that I, Andrew A. Syzdek, a citizen of the United States, residing in the city of Amsterdam, county of Montgomery, and State of New York, have invented a new, original, and ornamental Design for a Hat, of which the following is a specification, reference being had to the accompanying drawing, forming part thereof.

I claim:

The ornamental design for a hat, as shown.

ANDREW A. SYZDEK.
